UNITED STATES PATENT OFFICE.

ARTHUR F. LEVITT, OF LOS ANGELES, CALIFORNIA.

COMBINED GRIZZLY AND BALL MILL.

Application filed July 11, 1927. Serial No. 204,855.

My invention is a combined grizzly and ball mill in which a rotating drum has screen bars therein, forming a grizzly, and in which balls act on the material in the drum.

5 An object of my invention is the construction of a ball mill having screen bars therein forming a grizzly, and in which the balls are carried around in the rotation of the drum by the said grizzly bars, hence operating in a ball mill manner on the material being ground.

Another object of my invention is in allowing passage of aggregates between the grizzly bars into the portions of the mill having the balls, where it is acted on by the balls 10 and on the elevation of the balls through the rolling of the drum, the fine aggregate is dumped through the grizzly bars and allowed to sift through screens into a discharge spout.

In constructing my invention I utilize a 20 drum of large diameter and of comparatively short length in an axial direction. This drum has annular tracks thereon supported on rollers, at least one of which may be employed to drive the drum. Inside the drum and extending lengthwise thereof between the heads, there are a plurality of crossing rows of bars forming a segmental grizzly arrangement internally of the drum. There are balls of different sizes in each of these segmental parts. 30 The aggregate is fed into the drum at about its center and after passing through the various grinding operations due to the rotation of the drums, it is discharged through screens installed in the segmental parts.

35 My invention is illustrated in the accompanying drawings, in which:

Figure 1 is a vertical longitudinal section of my mill taken on the line 1-1 of Fig. 2 in the direction of the arrows.

40 Figure 2 is a vertical transverse section taken on line 2-2 of Fig. 1 in the direction of the arrows.

Figure 3 is a side elevation of the drum taken in the direction of the arrow 3 of Fig. 2.

45 Figure 4 is an end elevation of the mill.

Figure 5 is a vertical section through a combined mill and amalgamator.

Figure 6 is a side elevation partly broken away of a construction of Fig. 5.

50 Figure 7 is a detail section on the line 7-7 of Fig. 5 showing the manner of mounting the amalgamator plates.

Figure 8 is a partial vertical section through another type of combined mill and amalgamator,

Figure 9 is an edge view of a mill used for drying, burning or calcining material.

In constructing the drum this has a cylindrical structure 11 to which are secured annular angles 12 on the inside and to the inner flange 13 of these angles there is secured a back plate 14, this being a large disk, and a front plate 15, also a disk. The front plate has an infeeding opening 16 preferably circular. A plurality of tracks 17 which are annular are secured to the outside of the cylindrical part 11 of the drum. In the illustration shown, one of these tracks is formed as a large gear with teeth 18. The drum is supported on rollers 19 journaled in a suitable manner and supported on a suitable base 20. At least one of these rollers is constructed as a pinion 21, mounted on a rotatable shaft 22 and driven from the pulley 23, thus rotating the drum. 75

Internally of the drum there are rows 24 and 25 of bars similar to bolts, which extend longitudinally of the drum, that is, between the plates 14 and 15. These rows are preferably arranged at right angles, one to the other, and are illustrated as being substantially tangential to the circle forming the opening 16. Thus these rows of bars form grizzlies, and, with the inside of the cylinder 11, form segmental grinding chambers 26. 85

At certain parts of the periphery of the drum 11 there are screen bars 27 with spaces 28 therebetween, these bars extending around part of each segmental grinding chamber 26. Secured to the outside of the cylinder 11 there 90 are brackets 29 which hold a foraminated screen 30 in position. These screens may be of any desired mesh and are designed to be insertable and removable so that the material may be ground to the desired size. 95

Mill balls 31 are located in each of the grinding segments 26. In the illustration shown the balls in the different segments are of different sizes, although this is optional. They are maintained as separate units, confined in position by the drum 11 and the rows 24 and 25 of the bars forming the grizzly. Hence when a drum rotates, the balls roll on the inside of the drum on each other and on the grizzly bars, and moreover 100 the balls are carried up above the horizontal diameter of the drum and drop downwardly, giving a certain impact.

The aggregate is fed into the drum through the feed spout 32 and is discharged through 110

a discharge chute 33 which has lateral extension chutes 34 carried partly circumferentially around the drum and up to substantially the horizontal diameter. The chute 35 discharges into a discharge pipe 35.

The manner of operation of my combined ball mill with the grizzlies is substantially as follows:

- As the aggregate is dropped into the drum 10 it may pass into the small chambers 36 between the parallel rows of grizzly bars, or it may strike these bars, passing therethrough, depending on the spacing of the bars and the position of the drum in its rotation. As the 15 aggregate is free to pass through the bars it finds its way into the segments having the balls and there it is subjected to a grinding action. The balls roll one on the other and on the aggregate and are also lifted above 20 the horizontal, dropping with a certain impact against the aggregate.

I find it advisable to space the grizzly bars different distances apart, making segments with screen grizzlies, allowing different size 25 aggregate to enter into such grinding segments. The balls in said segments are also graduated in size in accordance with the size of the aggregate, so that the fine material will readily fall out of the segments designed for 30 the large aggregate and enter the segments suitable for the small aggregate. Practically immediately after the material is ground small enough to pass through the discharge screens 30, it finds its way clear through into 35 the discharge chutes; hence material which is ground sufficiently fine is not worked over and over again, but the action of the mill is practically confined to dealing with aggregates larger than the product.

40 From the above description it can be seen that I have developed a simple type of ball mill in which the grizzlies enter as an essential element in the grinding and these grizzlies function to screen the material in the 45 mill. I have, therefore, not only made an invention in the mill itself, but in the method of grinding.

For some types of work I find it advisable to have openings 40 in the back plate, these 50 openings being preferably made in the shape shown in Fig. 3 and are opposite the side of each of the grinding chambers 26. Screens 41 are secured at these openings by any suitable framing. Outside of the openings there 55 is a flared collar 42 secured to the plate 14 and partly surrounding the lower edge of this collar there is a lateral discharge chute 43 (note particularly Figs. 3 and 4).

I also, in some cases, have a water pipe 44 60 discharging water into the feed spout 32 in order to wash material passing through my mill.

In order to block any of the screens I provide a series of bent plates 45, illustrated in 65 Fig. 1, which are secured by screws or the

like to the periphery of the drum 11 over the screens 30. This prevents outlet of material at such screens and forces it out through the screens 40. I may utilize one or more of these plates so that when washing material by injecting water, the light slime may be floated out of the side screens 41 and discharge by the lateral discharge chute 43.

Then again, for ordinary grinding in which the product is to be discharged through 70 the screens 30, I may attach side plates 46 by screws or the like to the back plate 14 and close in the screens 41, thus forcing all the product through the screens 30. It is to be understood that I may use dry material for 80 grinding, or I may introduce water therein, and if it is desired merely to wash aggregates of dust and slime for concrete work, a plentiful supply of water may be flushed into the mill while it is in operation, and the material subjected to comparatively little grinding.

In some cases for grinding certain classes of material I place a row of bars 47 between the heads 14 and 15 of the drum and adjacent the cylindrical wall 11 and between the rows of bars 24 and 25. Thus the balls by being confined to the four segments shown are kept out of contact with the periphery of the drum and material which is too coarse 90 to pass through the screens settles between this peripheral row of grizzly bars, and the inside of the drum adjacent the screens.

In the combined mill and amalgamator as 100 illustrated in Figs. 5 and 6, I utilize somewhat the same type of drum, this having an outer shell 50 with heads 51 and 52, and across the heads I provide rows of bars 53, 54 and 55, forming grizzlies. The bars 54 and 55 are preferably arranged at right angles to each 105 other and parallel to diameters of the drum. The curved row 55 is concentric to the outer shell of the drum. Balls 56 are inserted in the various segments, and material is fed into the drum through an opening 57 in one 110 of the heads, through a charging chute 58, there being a water supply pipe 58' adjacent thereto. The drum is provided with a number of openings 59 in the shell and these have screens 60 fitted thereover. The screens are 115 preferably secured to the shell 50 by a hinge 61 at one end, and by a lock 62 at the other end, this lock being controlled by a key.

Internally of the drum and spaced between the row 55 of grizzly bars and the periphery 120 of the drum there are a plurality of amalgamating plates 63, such plates having perforations 64 therethrough; the plates are removable and are secured in slotted lugs 65 on the opposite heads 51 and 52 of the drum, and may be secured in place by set screws 66, or other suitable clamping means. It will be noted that there are provided inner and outer rows of these plates, the plates preferably being flat and staggered, one in relation to the 130

other. The plates for the most part are directly outside of the segmental grinding chambers.

The drum has peripheral tracks 67 supported on rollers 68 mounted on a suitable frame 69, one or more of which may be driven in any suitable manner. The crushed product of the mill is discharged into a collecting chute 70 and discharged through a hopper 71.

10 In the construction shown in Fig. 8 the arrangement of grizzly bars is substantially the same as that set forth in connection with Figs. 5 and 6, but in this case the amalgamating plates 72 are substantially radial and 15 are provided with apertures 73 therethrough. In addition there are plate-holding lugs 74 positioned directly outside of the cylindrical row of grizzly bars 55. The outside screens are of the same construction as set forth in 20 Figs. 5 and 6 and may be open.

The manner of operation and functioning of my combined mill and amalgamator as shown in Figs. 5 through 7 is as follows:

The material to be crushed is fed into the 25 mill, as above described, and a certain amount of mercury is also charged in the mill, this being in proportion to the metal that it is desired to amalgamate, the amount required for gold being proportionate to the assay of 30 the ore being crushed, or the deposit being worked. In the continued rotation of the drum the ore is crushed by the balls and grizzlies and if placer deposits are being worked, the material is ground and worked over, be- 35 coming in a fine disintegrated condition, so that the free gold may contact with the amalgamating plates 63 which are suitably plated, preferably on both sides, and on account of the mercury mixing in with the ore an amalgamate is formed on the plates. The tail- 40 ings pass through the screens. After a suitable run, and when it appears that the plates require cleaning, the screens 60 may be opened and the plates removed and scraped.

45 When my mill is used for working placer deposits where quartz gold may be present, the crushing of the quartz by the balls and grizzlies separates the free gold and the placer gold, where nuggets may be present. 50 This, together with the washing operation by an influx of water, separates the free gold, which is washed through the grizzlies and collects on the screens; also, the flat placer gold separates from the aggregate and like- 55 wise collects on the screens. This gold is then in good condition for amalgamation and, as the grizzlies protect this gold from again coming in contact with the balls, it is left intact in its original condition for amalgamation treatment. The mill is then periodically cleaned and the free gold collected off the screens. The rows of grizzly bars con- 60 centric to the outer shell of the drum prevent the gold from being re-ground or pulverized 65 in the operation of the mill, as frequently

happens in ordinary milling operations. The tailings are then free to take over the ordinary course through the screens, and any iron sufficiently valuable, in other words carrying gold, may be concentrated and worked 70 in the ordinary way.

In the construction shown in Fig. 9 the drum may be substantially similar to that shown in Figs. 1 through 4, it being preferable, however, to omit the screens on the 75 side. As this type may be utilized for drying, burning or calcining the product, a fuel pipe 80 has a nozzle extending into the drum through one of its heads. The flame causes the grizzly bars and the balls to become very 80 hot, therefore, as the material is being worked and ground it becomes thoroughly dried, the moisture escaping upwardly through the screens, and the dry product discharged through the bottom screens. The same pro- 85 cedure is followed in more intense heating, such as for burning or calcining a product, as in treating kieselguhr.

A characteristic feature of my mill is that it is self-cleansing, the fine material, by the 90 action of the mill, is cleared from the grizzly bars and from the crushing apparatus. Moreover, as the fines readily pass through the grizzlies and they are not subjected to re- 95 grinding, there is no sliming of the ore, as when once ground and sufficiently fine the material is not subjected to any further grinding.

I find it advantageous to have grizzly bars 47^a positioned adjacent the shell of the drum 100 at the outer ends of the small chambers 36, as shown in Fig. 1, and to have fairly large balls 31^a for filling in such chambers. In the rotation of the drum these balls are free to roll from one chamber to another, rolling 105 on the lowermost of the parallel rows of grizzly bars 24. This gives a pulverizing action to the material immediately it has been fed into the drum by the feed spout 32.

In the construction of Figs. 5 through 8 110 the bars at the extremities of these small chambers are designated 55^a and the balls operating in such chambers as 56^a, the action being the same as described above, and in addition, these grizzly bars prevent the balls 115 and the material immediately on being fed in coming in contact with the amalgamating plates.

Various changes may be made in the principles of my invention without departing 120 from the spirit thereof, as set forth in the description, drawings and claims.

I claim:

1. A mill comprising a rotatable drum having a series of bars extending lengthwise 125 thereof in transverse and peripheral alignment, said bars forming a grizzly, balls in the drum adapted in rotation of the drum to roll against the transverse bars and against the peripheral bars, and means to feed material 130

to the drum and discharge the ground material therefrom.

2. A mill comprising in combination a rotary drum having a plurality of sets of bars extending lengthwise of the drum and spaced from the walls of the drum, balls disposed within the drum and adapted to encounter the bars upon rotation of the drum, and means to feed material into the drum and 10 discharge the crushed product.

3. A mill comprising a drum, a plurality of sets of bars extending lengthwise therein, said bars being arranged to separate different segments of the circumference of the 15 drum, balls retained in said segmental sections by the bars of each set, and means to feed material to the drum and discharge the crushed product.

4. A mill comprising a rotatable drum 20 having a plurality of sets of bars extending lengthwise therein, said bars of each set being arranged to separate segments of the drum, balls located in each of said segments, the periphery of the drum having openings at 25 each of the segments to discharge the crushed product, and means to feed the material for crushing into the drum.

5. A mill comprising a rotatable drum having heads on opposite sides, a plurality of sets 30 of bars, each set being arranged to separate a segmental section of the drum, each segmental section having openings in the periphery of the drum with screens at such openings, balls in each of the segmental sections 35 and retained therein by the said bars of each section, means to feed material for grinding through one of the heads into the center of the drum, and means to collect the crushed product discharged through the screens.

40 6. A mill comprising in combination a drum having a cylindrical periphery with heads connecting the peripheral part of the drum, a plurality of sets of bars connecting the heads, said sets each having two rows with 45 a substantially right angular corner, the corner being near the center part of the drum, the sets of bars and the section of the periphery of the drum separated by the rows of bars forming segmental grinding chambers, 50 the periphery of the drum at the segmental grinding chambers having openings with screens adjacent thereto, sets of balls in each of these segmental grinding chambers, retained therein by the bars and the peripheral part of the drum forming each of such chambers, one of the heads having a central opening to receive material for grinding, and a discharge chute to collect the crushed product passing through the screens.

60 7. A mill comprising a rotatable drum having heads on opposite sides, a plurality of sets of bars extending lengthwise of the drum between said heads, said sets being arranged to form grinding chambers, balls in said 65 grinding chambers, one of the sides having

a series of openings with screens, and means to discharge material passing through the screens.

8. A mill comprising a rotatable drum having heads on opposite sides and a peripheral 70 section, a plurality of sets of bars extending between said heads, said bars being arranged to form segmental grinding chambers in the drum, balls in said chambers, the periphery of the drum having a series of openings with 75 screens, one of the sides of the drum having openings with screens, means to feed material into the center of the drum from one side, and means to discharge material passing through the screens at the side and through 80 the screens in the periphery of the drum.

9. A mill comprising in combination a rotatable drum having a peripheral shell connected by opposite heads, a plurality of rows 85 of bars forming sets connected lengthwise of the drum between said heads, forming grizzlies, one row of bars being concentric to the shell, and connecting rows of bars extending inwardly therefrom forming segmental grinding chambers, and balls in said 90 chambers.

10. A mill comprising in combination a peripheral shell having opposite head plates, a plurality of sets of bars connected lengthwise of the drum to said heads, said bars forming grizzlies, the bars being arranged to form segmental grinding chambers with a row of bars concentric to the shell, and lateral rows of bars extending from the concentric row inwardly, balls in said grinding 100 chambers, the shell having openings there-through with screens at the openings.

11. A mill, as claimed in claim 10, one of the heads having openings with screens, the screens being positioned opposite the grinding chambers.

12. A mill comprising in combination a drum having a peripheral shell connected by head plates, a plurality of sets of bars connecting the heads, one set of bars being concentric to the shell, other sets extending inwardly therefrom and forming segmental grinding chambers with balls therein, a series of amalgamating plates positioned in the drum between the shell and the concentric 110 row of bars, means to feed material into the shell and to discharge the crushed product.

13. A mill comprising in combination a peripheral shell connected by plates forming heads, a plurality of rows of bars connecting said heads, said bars being arranged to form segmental grinding chambers with a series of bars concentric to the shell and rows of bars extending inwardly therefrom towards the center of the shell, there being sets of 125 balls in each grinding chamber, a plurality of amalgamating plates positioned outside of the concentric row of bars and inside of the shell, the shell having a series of openings with screens at such openings, means to feed 130

material into the drum, and means to catch the ground product falling through the screens.

14. A mill, as claimed in claim 13, the amalgamating plates being arranged at an inclination to the periphery of the drum and being removably connected to the heads.

15. A mill comprising in combination a shell having opposite heads connected thereto, a series of sets of grizzly bars connecting lengthwise of the drum the heads arranged to form segmental grinding chambers with balls therein, means to feed material into the drum, means to discharge hot gases into the drum, and openings in the drum having screens.

16. The method of grinding comprising feeding coarse material into a drum having a plurality of grinding chambers, each arranged with longitudinal bars spaced transversely and circumferentially and balls retained by said bars in the grinding chambers, the material passing through the bars and being operated on by the balls, and being discharged downwardly through screens.

17. The method of grinding and amalgamating comprising introducing material to be treated into a rotating drum, crushing and grinding the material in a plurality of grinding chambers, each having sets of bars with balls retained therein, the material being ground by the balls and by contact with the bars, the fine material dropping through the bars and passing over amalgamating plates carried by the drum.

18. The method of grinding and amalgamating comprising introducing a material to be treated into a rotating drum, grinding the material in a plurality of grinding chambers, each having an enclosure of bars spaced apart with balls retained therein, the material being ground by the balls and pass-

ing through the bars, and after grinding, the material falling through the bars on to amalgamating plates secured in the drum, and after passing over the plates, the material being screened by screens connected with the drum.

19. The method of grinding and heating material comprising introducing a material to be treated into a rotating drum, grinding the material in grinding chambers formed by sets of longitudinal bars spaced transversely and circumferentially with balls retained in position by the bars, the material passing between the bars and being ground by the balls, discharging heating gases into the drum and allowing the ground product to discharge through screens in the periphery of the drum.

20. A mill comprising in combination a drum having a peripheral shell with heads at opposite sides of the shell, a row of grizzly bars connecting lengthwise of the drum between the heads and positioned concentric to the shell, a plurality of sets of other grizzly bars connected lengthwise of the drum between the heads, some of which extend inwardly from the said concentric row of bars towards the center of the drum and form segmental grinding chambers with smaller grinding chambers between the segmental chambers, each of said chambers having grinding balls therein, the grinding balls in the smaller chambers being free to pass from one chamber to another but the balls in the segmental chambers being retained therein, means to feed material into the drum and discharge material from the drum, and means to rotate the drum.

In testimony whereof I have signed my name to this specification.

ARTHUR F. LEVITT.
